UNITED STATES PATENT OFFICE.

PETER BROADBOOKS, OF BATAVIA, NEW YORK.

PLIERS.

SPECIFICATION forming part of Letters Patent No. 699,909, dated May 13, 1902.

Application filed March 30, 1901. Serial No. 53,592. (No model.)

To all whom it may concern:

Be it known that I, PETER BROADBOOKS, a citizen of the United States, residing at Batavia, county of Genesee, and State of New York, have invented a certain new and useful Improvement in Pliers, of which the following is a specification.

My invention relates to a new and useful improvement in pliers, and has for its object to construct pliers in which the handles are pivoted together in such a way as to give to the jaws a compound leverage, which will make them powerful and at the same time simple in their operation. A further object of my invention is to construct the same of few parts and have such parts so that they are readily assembled, so that the pliers will be inexpensive to make, convenient in operation, and strong in all their parts.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 represents a side elevation of my pliers, showing side wire-cutters attached to the jaws. Fig. 2 is a similar view showing the plates upon one side which connect the handles, with the jaws removed. Fig. 3 is a section on the line 33 of Fig. 1. Fig. 4 is a section on the line 44 of Fig. 1. Fig. 5 is a side elevation similar to Fig. 1, showing the end cutters substituted in place of the jaws.

In carrying out my invention as here embodied, A represents the handles of the pliers, which are pivoted together at the point B.

C are the jaws, which are pivoted together by the pivot D.

E represents plates which are arranged in pairs upon each side of the handles and jaws. These plates cross each other upon each side of the pliers and are pivoted together upon the pivot D. The forward end of one of the plates, upon each side, is pivoted to the jaws C at the points E', and the heel end of one of the plates, upon each side of the handles, is pivoted to

said handles at the points F. Thus the jaws C are pivoted together independently of the handles A and are only connected together by means of the plates E. By reason of two of the plates being pivoted to one handle and the other two to the other handle and said plates being thus pivoted together upon the same pivot as the jaws and then two of the plates, one upon each side, being connected to the jaws at a point between the pivot D and the outer end of the jaws will cause a compound leverage to be employed when the handles A are open or closed. This will give great power to the jaws with a very simple construction.

G represents cutter-plates, which may be formed with or secured to the jaws C (in the drawings they are shown as formed separate from the jaws) and are riveted, one to each of the jaws, by the rivets H and also by the pivots or rivets E'. The cutting-plates meet at the line I and are milled or ground to a knife-edge for the purpose of cutting wire, &c. These cutting-plates instead of being riveted to the jaws could be formed solid with one set of the side plates E; but the more preferable form would be to have them separate, so as to replace the same when the cutting edges need sharpening or if the plates themselves should be damaged in any way.

In Fig. 5 I have shown how the jaws C could be removed and the end cutters J substituted in the place thereof.

The advantages of my invention are that by employing this form of construction great power can be employed with an instrument which is comparatively simple and cheap to construct and the parts assembled in such a way that if any part should become damaged it can be readily interchanged for a new one, and a further advantage of my device is that the jaws being pivoted independent of the handles any form of jaws can be readily substituted without removing any parts except the jaws themselves.

Of course I do not wish to be limited to the exact construction here shown, as slight modifications could be made without departing from the spirit of my invention.

Having thus fully described my invention, what I claim as new and useful is—

1. In pliers, a pair of handles pivoted together, a pair of jaws pivoted together inde-

pendent of said handles, plates arranged in pairs upon each side of the handles and jaws, said plates crossing one another and being pivoted together upon the same pivot as the 5 jaws, one end of said plates upon each side being connected to the jaws, the heel end of the plates upon each side being connected to the handle, substantially as described and for the purpose specified.

10 2. In pliers, a pair of handles pivoted together, a pair of jaws pivoted together at their heel ends independent of the handles, a pair of plates, one upon each side of the jaws and handles, one end of said plates being pivoted 15 to one of the jaws, the other end of said plates being pivoted to one of the handles, a second pair of plates, one upon each side of the jaws and handles, said second pair of plates adapted to cross the first-named pair of plates and 20 be pivoted at one end to the other jaw and at their other end to the other handle, said plates being all pivoted together upon the same pivot as the jaws, cutting - plates secured to or formed with said side plates, the cutting edges 25 adapted to meet and lie parallel with one another when the jaws are closed, substantially as described and for the purpose specified.

3. In combination, in pliers, a pair of handles A pivoted together, a pair of jaws C pivoted together independent of the handles,

cross-plates E arranged in pairs upon each side of the jaws and handles and pivoted upon the same pivot as the jaws, two of said plates, one upon each side of the jaws being pivoted at one end to one of the jaws at a point between the pivotal point of the jaws and the end of the same, the other end of the same plates being pivoted to one of the handles at a point intermediate of the pivotal point of 35 said handles and their ends, the other two 40 plates, one upon each side of the jaws, being pivoted at one of their ends to the other jaws at a point intermediate between the pivotal point of the jaws and the end of the same, and the other end of the same plates being 45 pivoted to the other handle at a point intermediate of the pivotal point of the handles and their ends, wire-cutters secured to or formed with one side of the jaws having cutting edges adapted to meet and lie parallel 50 with one another when the pliers are closed, substantially as and for the purpose specified.

In testimony whereof I have hereunto affixed my signature in the presence of two subscribing witnesses.

PETER BROADBOOKS.
